FIG. 5.

INVENTOR
BENSON CLIFFORD GOODMAN
BY *Edwin Leisohin*

ATTORNEY

UNITED STATES PATENT OFFICE

BENSON CLIFFORD GOODMAN, OF FAR ROCKAWAY, NEW YORK

LOOM

Application filed January 27, 1928. Serial No. 250,065.

This invention relates to improvements in filling detectors for looms.

My invention has for its object to provide an attachment for the shuttle to detect when the filling is running out on the quill in time to change the latter in an automatic magazine or if the loom is without the automatic magazine to stop the operation just before the filling runs out to eliminate the necessity of the weaver's finding the pick.

I accomplish this object by means of a device hereinafter described, and set forth in the claims, and illustratively exemplified in the accompanying drawings, in which, Figure 1 is a plan view of a shuttle having my improved detector embodied therein; Figure 2 is an inside plan view of one wall of the shuttle showing the detector in detail; Figure 3 is a substantially longitudinal sectional view of the shuttle and detector taken on lines 3—3 of Figure 2; Figure 4 is a modification of the detector and its connection with the loom; and Figure 5 is a sectional view of the same.

It might be mentioned here that the present invention is merely for the purpose of translating the running out of the yarn on a quill into a mechanical motion for the purpose of effecting the operation of the loom stopping device or automatic magazine.

Referring now to the drawings, 10 denotes a shuttle of any well known design adapted to receive and carry a bobbin 11 which is held in position by suitable bobbin clips 12 arranged in one end of the bobbin opening 13 in the body of the shuttle. The yarn 14 is wound upon the bobbin 11 in the usual manner, care being taken to provide a reserve of any number of picks or portions of picks desired to be left on the bobbin at the time of indication for transfer in order to enable the shuttle to return to the magazine end of the lay without breaking the strand, or detecting the end if not a magazine loom.

The detector comprises a shoe 15 pivoted or hinged at one end on a pintle 16 which is supported normally in upright position between a pair of ears 17 projecting from one end of a plate 18. The plate 18 is fixed on the wall of the shuttle 10 and extends from the top to the bottom of the wall in a position

closely adjacent to bobbin clips 12, as illustrated particularly in Figure 2. Suitable wood screws 19 are used to mount the plate 18 on the shuttle wall. The shoe 15 itself comprises a plate rounded at its sides to present a smooth rounded surface to bear upon the yarn or filling 14 at the end of quill or cap. The shoe 15 is constantly urged in the direction of the filling by a spring 20, shown in Figure 3. At its extreme free end the shoe 15 carries a metal contact finger 21, which is mounted on the inside of the shoe and projects towards the outside of the shuttle 10 through an opening 22 therein, and which makes electrical contact with a second plate 23 mounted on the inner face of the shuttle wall. The plate 23 is disposed parallel to the first plate 18, is attached to the wall by screws 24 and is of a length to project substantially halfway the height of the bobbin wall. One side of the plate 23 projects over about one half of the opening 22, so that when the yarn 14 has run out the shoe 15 will have moved away from the shuttle wall under influence of the spring 20, and the finger 21 will have been brought into contact with the plate 23. In order that the contact finger 21 and plate 23 may open or close an electric circuit for operating a magnet or other device, I provide the shuttle box 25, which on a

magazine loom is the plain side, with an opening or slot 26 in each lateral flange thereof. The slots 26 open toward the shuttle path and each is provided with an insulating lining 27 in a metal box, in a wood box the wood itself acts as insulation, and a pole pin 28 projecting in an upright direction through a tube of insulation 29 to the outside of the shuttle box 25. The portions of the pole pins 28 bridging the slots 26 carry one end of contact brushes 29'. The brushes 29' are made of yieldable metal strips and the free ends project outwardly through the slots 26 and into the shuttle path. The circuit

contacts between the brushes 29' and the plates 18 and 23 of the shuttle 10 are made through projections 30 and 31 of the plates 18 and 23, respectively, the projections being embedded in the wall of shuttle and projected for a considerable distance toward the

- eye end of the shuttle, as illustrated clearly in Figures 2 and 3. When the thread on the shuttle bobbin has reached a point allowing the circuit to close, the current passes through the upper pin 28', thence to the upper brush 29' and through upper plates 31 and 23 to the shoe 15 and lip 21 from which it crosses over through the lower plate 30 and lower brush 29' and out through lower pin 28".
- 10 The pole pins 28 are connected to an electromagnet 32 through a circuit 33, and battery 34 or other source of energy, the armature 35 of the magnet 32 being utilized to operate any of the devices now being employed either to stop the loom or to set an automatic magazine into operation. Contacts may be on either or both sides of the box or top or bottom or any combination thereof, the shuttle wiring being made to correspond. A switch is used in combination with the loom shedding device so that when the loom is idle the current is turned off.
- 15 Referring now to Figure 4, the shoe 15 is provided with a lever projection 36 which operates through an opening 37 in the wall of the shuttle 10. The outer end of the lever 35 as the yarn is used up projects farther out until at a point when the filling is running out, the lip of the lever is beyond the shuttle 20 wall and comes into contact with a trip 38 carried by the shuttle box 25 on the side away from the reed. The trip 38 is illustrated in a conventional figure in the drawings, the invention being to a means for imparting usable motion from the shuttle which may be used to either stop the loom or operate the 25 automatic magazine as desired.
- 20 It is preferable of course that in setting up the present detector the latter will detect the running out of filling at a point in the operation of the loom just before the yarn on the quill is exhausted, thereby bringing the loom to a stop on the same pick on which detection occurs. The same arrangement 25 used with an automatic magazine is connected with the latter which is brought into operation and a transfer made two picks later or at such a time, when colors are employed, as the box chain will bring the indicated color, 30 i. e. the quill running at time of detection, for transfer again.

35 Indication may occur on front center or any other desired positions of the crank shaft.

40 Having now described my invention and the manner in which the same operates, what I claim and desire to secure by Letters Patent is:

- 45 1. In a loom, the combination of a shuttle box and a shuttle, a yarn filled bobbin arranged in said shuttle, a detector disposed longitudinally of the bobbin and pivoted at one end in said shuttle and provided with a rounded nose yieldably urged towards the 50 bobbin and into constant contact with the

55 exterior of the yarn on the bobbin, an electrical contact carried in the shuttle and completed when the yarn is exhausted from the bobbin and the detector contacts with the said contact, and an electric circuit including an electromagnet controlled by said contact and position of the detector.

60 2. A detector for a shuttle used in a loom, comprising a pivoted at one end metal shoe disposed longitudinally of the shuttle and provided with a rounded nose yieldably towards the bobbin and urged into contact with the exterior of the filling in the shuttle, spaced plates embedded longitudinally in said shuttle and exposed at one side thereof, one plate being electrically connected with the shoe, a contact member at the free end of the shoe and movable into contact with the second plate when the filling is exhausted to provide an electrical conductor from one plate to the other.

65 3. A detector, as claimed in claim 2, including a shuttle box to slidably receive and guide the shuttle, and brushes mounted longitudinally in the shuttle box and arranged to contact with the said plates, respectively, to form an electrical connection.

70 In testimony whereof he has affixed his signature.

BENSON CLIFFORD GOODMAN.
